Inventor:

Will J. Lawder,
By Wm. M. Lane Attorneys:

UNITED STATES PATENT OFFICE.

WILL J. LAWDER, OF WASHINGTON, DISTRICT OF COLUMBIA, ASSIGNOR TO CHAMBERLIN METAL WEATHER STRIP COMPANY, OF DETROIT, MICHIGAN, A CORPORATION OF MICHIGAN.

WEATHER-STRIP.

No. 872,434.

Specification of Letters Patent.

Patented Dec. 3, 1907.

Application filed July 19, 1907. Serial No. 384,622.

To all whom it may concern:

Be it known that I, WILL J. LAWDER, a citizen of the United States, residing at Washington, in the District of Columbia, 5 have invented certain new and useful Improvements in Weather-Strips, of which the following is a specification, reference being had therein to the accompanying drawing.

This invention relates to improvements in 10 weather strips, and has for its primary object the provision of means for reinforcing and stiffening the sealing rib or flange thereof whereby to preserve the same against deflection or bending from its normal operating 15 position.

Although the invention is equally applicable to other types of strips, the same is primarily an improvement of the sheet metal strip disclosed in the patent to Albert Clinton 20 Sims No. 424,905. In the use of strips made in accordance with the patent referred to, and more especially in those instances where the strip is applied at the bottom of a window casing or frame with the rib of the strip in an 25 upstanding position, the flange becomes bent over or distorted and its use impaired, for example, by a person accidentally stepping thereon in washing windows or by striking the same with extraneous objects.

30 A convenient embodiment of the invention resides in the introduction of a reinforcing or stiffening strip in the space between the parallel sides of the folded sealing rib or flange, and said strip being of a width not only to 35 fill said space, but to project a substantial distance beyond the plane of the inner edges of the rib or flange and into a kerf or groove formed in the window frame or sash whereby 40 to be securely anchored in the frame and hold the sealing rib or flange in proper position.

The details in the construction and arrangement of the parts will be apparent from the detailed description hereinafter contained when read in connection with the accompanying drawings forming part hereof, and wherein the before mentioned convenient embodiment of the invention is illustrated.

45 In the drawings: Figure 1 is a perspective view of the lower portion of a window frame and sliding sash mounted therein, the improved strip being applied to the bottom of the frame and the lower rail of the sash grooved

to receive the sealing rib or flange; and Fig. 2 55 is an enlarged cross sectional view.

Referring more specifically to the drawings, wherein like reference characters refer to corresponding parts in the two views, A represents the sash frame or casing, and B 60 the slideable sash therein, these being of any ordinary or preferred construction.

The lower rail of the sash B is provided with a groove C in its under surface longitudinally thereof for the reception of a sealing 65 rib or flange D secured to the upper surface of the bottom of the frame or casing A. In the present instance this rib or flange is formed by bending a piece of sheet metal upon itself whereby the rib has a smooth 70 outer edge and substantially parallel sides, and offsetting the edge portions of the sheet approximately at right angles to the rib to provide securing flanges E. The flanges are fastened to the frame in the usual manner, 75 either by tacking them both to the frame or by tacking the outer flange and running the inner flange beneath the sill F as clearly shown in Fig. 2. In the space on the interior of and between the parallel sides of the 80 sealing rib or flange I introduce a bracing or stiffening strip G, this strip being considerably greater in width than the width of the sealing rib whereby to project to a substantial extent into the frame as at H, the latter 85 being provided with a kerf or groove for that purpose. By this means it will be appreciated that the strip G is firmly anchored in the frame and that its projecting portion will serve to effectually prevent bending over or 90 distortion of the sealing rib or flange.

While I have specifically described but one embodiment of my invention, it will be apparent to those skilled in the art that the invention comprehends any desired sealing rib 95 or flange and securing means therefor, in combination with an auxiliary anchored bracing or stiffening member.

I claim:

1. A weather strip having a sealing rib 100 formed of sheet metal folded upon itself, a bracing or stiffening member therein of a width to project a substantial distance therewithout whereby to be anchored, and a securing flange integral with and offset from 105 said rib.

2. A weather strip having a sealing rib formed of sheet metal folded upon itself, a

bracing or stiffening member therein of a width to project a substantial distance therewithout whereby to be anchored, and securing flanges integral with and offset from opposite sides of said rib.

5. In combination with a frame having a groove formed therein; a weather strip having a sealing rib arranged over said groove, said sealing rib being formed of sheet metal 10 bent upon itself, and a bracing or stiffening member introduced in the hollow interior of said rib and projecting outwardly therefrom and into the groove of said frame.

6. In combination with a frame having a 15 groove formed therein; a weather strip having a sealing rib arranged over said groove, said sealing rib being formed of sheet metal bent upon itself, a bracing or stiffening member introduced in the hollow interior of said 20 rib and projecting outwardly therefrom and into the groove of said frame, and a flange integral with said sealing rib offset therefrom and securing the rib in position.

7. In combination with a frame having a 25 groove formed therein, a weather strip having a sealing rib arranged over said groove, said sealing rib being formed of sheet metal bent upon itself, a bracing or stiffening mem-

ber introduced in the hollow interior of said 30 rib and projecting outwardly therefrom and into the groove of said frame, and flanges integral with said rib and offset in opposite directions therefrom securing the same in place.

8. In combination with a frame, a weather 35 strip member formed of sheet metal bent upon itself to form a sealing rib and secured to said frame, and having a rigid bracing or stiffening member in the hollow interior thereof, said member being anchored at its 40 edge to prevent lateral deflection of the sealing rib.

9. In combination with a frame, a weather 45 strip member secured thereto and having a projecting hollow sealing part closed at its outer edge and a rigid bracing or stiffening member therein anchored to said frame to prevent lateral deflection of said projecting sealing part.

In testimony whereof I affix my signature 50 in presence of two witnesses.

WILL J. LAWDER.
